MACHINE FOR INSERTING FASTENERS AND
FORMING THE HEEL SEAT OF SHOE
SOLESHiram Gordon and Albert C. Rogge, Columbus,
Ohio, assignors to Lock-On Heel Company,
Chicago, Ill., a corporation of Illinois

Application May 23, 1936, Serial No. 81,478

13 Claims. (Cl. 12—42)

The invention relates to the art of manufacturing shoes, and has special reference to an improved method and machine for inserting fasteners and forming the heel seat of a shoe sole.

5 The object of the invention is to apply and permanently secure a metallic heel fastening plate to the heel receiving area of a shoe outsole and simultaneously therewith trimming the outsole by removing surplus stock therefrom during the operation of securing the heel attaching plate to the outsole.

Hitherto, it has been customary in the operation of attaching heels to shoes with the aid of metallic fastening plates to subject a heelless 10 lasted shoe to the action of a cutter to trim the marginal portion of a heel seat in order that the cupped or concaved attaching face of a wood heel could be guided over the trimmed heel seat region of the outsole with the outer marginal edges 15 of the attaching surface of the heel in close fitting contact with the shoe upper and without the edges of the outsole, in the region of the heel, being exteriorly visible. Such a heel seat trimming machine has been disclosed in our prior 20 Patent No. 2,032,411 granted March 3, 1936.

Such heel seat trimming operations are common in the manufacture of shoes, whether the heels are attached to the shoes by the ordinary methods of nailing or when pronged metallic 25 plates of the type disclosed in the patent of Dopp 2,017,234 granted October 15, 1935, are employed.

The ordinary heel seat trimming operation, that is, the removal of surplus stock from the heel 30 region of a shoe outsole in order to adapt the latter for the reception of a heel body having a cupped face, requires considerable time whether it is done by machine, as is now mostly the case, or by hand, and it is, therefore, a cardinal object of the present invention to provide a method 35 and machine by which a metallic heel fastening plate of the pronged type is secured to an outsole in such a manner that it forms a finished heel seat and at the same time, during the attaching operation, removes or trims the surplus 40 stock from the outsole so that both operations may be carried out at substantially the same cost as either one considered separately.

It is another object of the invention to provide in combination with a heel plate attaching machine 45 means for producing transversely extending cuts or slits in the outsole of a shoe, so that the slits will extend inwardly from the opposite edges of the outsole in registration with the breast line of the heel body which is to be applied to the 50 outsole, whereby when a metallic fastening plate

having peripheral cutting edges is forced downwardly upon the outsole, during manufacture and in the operation of attaching the fastening plate, the said peripheral cutting edges will penetrate the stock of the outsole to effect the removal from the outsole of all surplus material from the heel region which would otherwise project beyond the marginal edges of the fastening plate.

5 A further object of the invention is to provide an improved method and means for securing accurate control in the matter of producing the breast line cuts in the outsole so that the same will exactly register with the breast lines of the heels applied to the shoes.

10 A still further object of the invention resides in the provision of shoe positioning means adapted to secure facility and precision in the matter of determining the positions of application of the metallic heel attaching plates, so that the latter will be exactly located as required when positioned on the outsole and operatively fastened to the shoe. With the above and other 15 objects and features in view, the invention will now be described in connection with the accompanying drawings and pointed out in the claims.

15 In the drawings:

Fig. 1 is a front elevation of the improved heel attaching machine comprising the present invention;

20 Fig. 2 is a side elevation thereof;

Fig. 3 is a horizontal sectional view on the plane indicated by the line III—III of Fig. 1;

Fig. 4 is a vertical sectional view on the plane disclosed by the line IV—IV of Fig. 3;

Fig. 5 is a vertical sectional view, the plane of which is indicated by the line V—V of Fig. 4;

Fig. 6 is a detail vertical sectional view on the plane indicated by the line VI—VI of Fig. 3;

Fig. 7 is a detail vertical sectional view taken 40 through the pressure cylinder and accompanying operating means for operating the breast line cutters;

Fig. 8 is a transverse vertical sectional view on the plane indicated by the line VIII—VIII of Fig. 3;

Fig. 9 is a longitudinal sectional view through one of the control valves used on the machine;

Fig. 10 is a vertical sectional view of the supporting table and presser head with a heelless 50 shoe in position prior to the attaching operation.

Fig. 11 is a similar view following the attaching operation;

Fig. 12 is a view illustrating the operation of 55

driving a locking pin into a heel to secure the latter to the shoe.

Referring more particularly to the drawings, a supporting frame or bed, indicated at 1, provided with vertical legs or end frames 2, effects the support of the heel plate attaching mechanism. Stationarily arising from the frame 1 is a standard 3 having its lower portion formed with a horizontal shelf 4 upon which is stationarily supported 10 an anvil block 5. The standard 3 at its upper end, and in vertical registration with the block 5, has secured thereto a depending cylinder 6 containing a pneumatically operated piston held in an elevated position by a coil spring. Secured 15 to this piston and projecting slidably through the lower end thereof is a piston rod 7, which carries at its lower end a pressing head 8.

The pressing head is provided at its lower end with a substantially concaved plate-receiving 20 surface 9 having spaced vertical recesses 10 which open to the surface 9. Adapted to be applied to the surface 9 and to be held by the head 8, when the latter is in its elevated position, is a metallic heel fastening plate 11. This plate comprises a 25 unitary stamped metallic body shaped to provide a heel seat and formed with marginal cutting edges 12, integral attaching prongs 13 and spaced depending heel attaching ears 14. The ears 14 are adapted to be positioned in the recesses 10, 30 and spring means coact with said ears when positioned within said recesses to detachably support the plate 11 in connection with the surface 9 of the pressing head. When thus attached to the head 8, the prongs 13 of the plate 11 and the 35 peripheral cutting edges 12 thereof extend in a downward direction so that the plate may be forced, upon the descent of the rod 7 and the pressing head 8, into fastened and seated relationship on the heel-receiving area of the shoe 40 outsole.

In the use of the machine, unfinished heelless shoes, of the type indicated at 15, are mounted on a last and include the usual outsoles 16 and uppers 17. The first step involved in applying a 45 heel fastening plate 11 to such a shoe, is to produce in the outsole 16 a pair of inwardly directed transverse cuts or slits 18, which must be, in order to secure proper fitting, disposed in registration with the breast line 19 of a heel, as indicated at 50 20, which is to be applied to the shoe.

In order to form these cuts or slits, the standard 3 supports at its upper end a cutter cylinder 21 which, as shown in Fig. 7, includes a piston 22, a vertically depending piston rod 23 and a 55 coil spring 24, the latter surrounding the rod 23 and is disposed between the lower end of the cylinder and the under surface of the piston 22. The lower end of the rod 23 projects through a stuffing box 25 provided in the bottom of the cylinder 21, and the extreme lower end of the rod 23, beneath said cylinder, is equipped with a threaded ferrule 26 which operates to maintain in seated relationship the spherical head 27 of a screw 28. The shank of the screw receives an 60 internally threaded adjustable collar 29 and a freely slidable block 30 is arranged on the lower end of the screw below and usually in spaced relation from the collar 29. Below the block 30, the screw 28 is equipped with lock nuts 31. 65 Pivotally connected as at 32 with the block 30 are the bifurcated arms of a crank 33, the latter being fixed upon the outer end of a cutter operating cam shaft 34. This shaft is journaled for partial rotation within a horizontally disposed bearing 70 75 formed in a cutter supporting bracket 36, the

latter being adjustably mounted for longitudinal movement on a supporting table 37 carried by and vertically movable with respect to the standard 3. As shown in Fig. 3, the back of the table 37 includes a rib 38 which is slidably mounted 5 within a dovetail groove 39 formed in the front wall of the standard 3. The lower end of the table 37 rests upon spring means 40 which is disposed between the lower horizontally extending portion of the standard 3 and the lower part 10 of the table 37, the normal tendency of the spring means 40 being to maintain said table in an elevated position so that a shoe initially positioned therein will be spaced from the anvil block 5. 15

The inner end of the shaft 34 is equipped with a cam 41 which, as shown in Fig. 5, is disposed between a pair of cutter carriers 42, the latter being pivoted as at 43 in connection with the bracket 36. These pivots are equipped with 20 springs 44, the normal tendency of which is to maintain the inner vertical edges of the carriers 42 in contact with the cam 41, as illustrated in Fig. 5. The bottom portions of the carriers are provided with angularly arranged cutters or 25 knives 45 which are used, upon the actuation of the cam, to produce the transverse breast cuts or slits 18 in the shoe outsole. The carriers 42 and the cam 41 are relatively connected by means of pivoted links 45a which operate to effect their 30 rapid and positive movement in unison.

Mounted on the lower part of the frame 1 is a bracket 46 which supports a pivoted foot pedal 47. The inner end of this pedal is connected with the lower end of a chain 48, which has its 35 upper end connected with an adjustable hook 49 carried by a block 50. Also connected with this block as at 51 is the lower end of a vertical rod 52 which has its upper end secured to the table 37. The operator of the machine, by depressing 40 the pedal 47, may thereby pull the table downwardly against the resistance of the spring means 40, so that a lasted shoe, supported in connection with the table, will be drawn downwardly into engagement with the anvil block 5. 45

To support a lasted shoe in connection with the table 37, the bracket 36 thereon has its under surface equipped with a pair of pivoted transversely spaced guards 53. These guards comprise metallic plates pivotally mounted in connection 50 with the bracket 36 as at 54, and have their forward ends formed with curved jaws 55, which are adapted to engage with the counter or upper 17 of the shoe when the latter is placed in an operative position within the machine for the reception of a heel attaching plate, as indicated at 11. These guards include curved edge portions 56 which slidably contact with the outer edges of the outsole 16 to support these edges of the outsole in spaced relation from the uppers 17, and 60 to protect the uppers from the action of the breast line cutters for the outsole. Further, the guards are formed with arcuate slots 57 for the reception of studs 58 projecting stationarily from the bracket 36, and wire springs 59 cooperate 65 with said guards for the purpose of rocking said guards about their pivots in a horizontal plane toward a shoe positioned between the same.

In order to control the position of a shoe within the machine so that the cutters 45 will produce the transverse slits in the outsole in registration with the breast line of the heel to be attached to the shoe, and to properly locate the heel area of the shoe outsole with respect to the fastening plate carried by the head 8, the table 70 75

37 is provided at one side with a horizontally extending flange 60. The upper surface of this flange has stationarily connected therewith, as indicated in Fig. 6, a gage block 61, which is provided with a pair of upstanding lugs 62 which are adapted to be received within longitudinally spaced slots 63 formed in the attaching surface of a gaging heel or templet 20', the latter corresponding in dimensions to the heel which is to be attached to the shoe.

10 A gage plate 65 is keyed as at 66 for controlled longitudinal sliding movement at the rear of the table 37. A clamping screw 67 may be operated to retain the plate 65 in its adjusted positions. 15 Carried by the upper surface of the plate 65 is a bar 68 having a recess 69 formed in its forward end which is adapted to be brought into engagement with the back edge of the gaging heel or templet 20' seated on the block 61. When this 20 engagement has been effected, as shown in Fig. 6, the screw 67 is tightened. Also carried by the plate 65, as shown in Fig. 4, is a heel rest plate 70, and the forward edge of the plate 70 is formed with a stationary lip 71 which is adapted to engage with the rand crease of a shoe when the heel of the latter is held in contact with the forward edge of the plate 70 and when gripped by the jaws 55.

25 A second gage plate 65a provided with a recess 64 to receive the block 61 of the table 37 in front of the plate 65 and this plate is provided with a breast engaging bar 72 which, as shown in Fig. 6, is adapted to be brought into engagement with the breast line of the attaching surface of the heel 20'. To effect this engagement of the bar 72, the gage plate 65a is formed at its forward edge in a down-turned lug 73 which has a swiveled engagement with an adjusting screw 74, the threaded shank of the latter being received within a 30 threaded opening provided in the forward portion of the flange 60 of the table 37. When this engagement has been effected, the bracket 36 is retained in its adjusted positions by means of a pair of vertically disposed clamping bolts 75.

35 Having thus generally described the operating parts of our improved heel plate fastening machine, the operation thereof may be summarized as follows:

40 A lasted unheeled shoe having an untrimmed heel seat is inserted in an inverted position within the machine so that the heel portion of the shoe will occupy the registering slots or openings formed in the table 37, the cutter carrying bracket 36 and the gage plate 65a, with the toe of the shoe pointing outwardly. Insertive movement of the shoe is limited by the contacting of the back of the upper with the forward edge of the plate 70 and by the engagement of the forward end of the lip 71 with the rand crease at the back of the heel seat. It will be understood that the operating positions of the plate 70 and the lip 71 are first determined by the placing of the gaging heel or templet 20' on the block 61 and the adjustment of the plate 65 so that the bar 68 thereon contacts with the back edge of the heel or templet 20' seated on the block 61. At the time the shoe 15 is thus inserted in the machine, the edge portions 56 of the jaws 55 will be located beneath the edges of the outsole 16 in alignment with the cutters 45. The operating positions of the cutters with respect to the outsole are then accurately controlled by the adjustment of the screw 74 which slides the bracket 36 bodily with respect to the table until the bar 72 contacts with the forward or breast edge of the heel or templet

20'. Through this means, the machine is readily adapted to receive and operate upon shoes to which any given predetermined style of heel is to be connected.

25 Following the insertion of the unheeled shoe into the machine, the operator depresses the foot pedal 47, which results in lowering the table 37 and the mechanism supported thereby on the standard 3, and against the resistance of the spring means 40, this lowering movement taking 10 place until the last 76, on which the shoe 15 is mounted, engages with the seat 77 provided in the upper end of a detachable plate 78 carried by the top of the anvil block 5. When this engagement has been effected, the operator by a 15 sidewise motion of the knee, engages a pad 79 provided on the lower end of a crank arm 80, which is connected with a rock shaft 81 journaled in connection with the frames 2. The back end of the shaft 81 is provided with a crank 82 20 with which is connected a variable length link mechanism 83 leading, as shown in Fig. 2, to a control valve 84, the latter being employed for governing the flow of compressed air from a suitable source of supply through a tube 85 which 25 leads to the top of the cylinder 21. The introduction of compressed air into the cylinder 21 results in the downward movement of the piston 22 therein and the actuation of the cam shaft 34, causing the cutters 45 to rock about their pivots 30 and produce the breast line slits or cuts 18 in the outsole, after which pressure on the pad 79 is released so that the control valve 84 will be closed against further inflow of compressed air and opened to provide a vent to the atmosphere 35 so that the piston 22 may return to its normal position on the action of the spring 24 and, also, to permit the cutters 45 to return to their opened or normal positions.

40 After the breast cuts have been produced, and the heel attaching plate 11 inserted into the head 8, which may be done prior to the insertion of a shoe into the machine, a hand operated control valve 86 is actuated while foot pressure is still exercised on the pedal 47 to retain the shoe on 45 the anvil block 5. The control valve 86 is connected by means of a pipe line 87 with the source of compressed air supply and is also connected by means of a pipe 88 with the cylinder 6. The introduction of compressed air into the cylinder 50 6 causes the descent of the piston therein and likewise the pressing head 8. The descent of the latter with the plate 11 positioned therein causes the prongs 13 of said plate to pass through both the outsole and insole of the shoe and by contact 55 with the metal heel base of the last 76 to be clinched inwardly so that the plate will be firmly and securely held in connection with the shoe, forming a finished heel seat. Simultaneously with the penetration of the prongs 13, the flanged 60 cutting edges 12 of the heel plate penetrate through the outsole and sever surplus material from the outsole in the form of a U-shaped blank, the forward edges of said blank having been previously severed by the formation of the slots or 65 cuts 18 therein as produced by the cutters 45.

70 Therefore, in accordance with the present invention, a heel attaching plate is secured to the heel region of an outsole and at the same time, the trimming of the heel seat takes place so that 70 when the fastening plate is completely attached, it produces a finished heel seat. After this operation, the control valve 86 is actuated to provide for the automatic elevation of the pressing head 8 and foot pressure on the pedal 47 is released so 75

that the table 37 may be elevated by the action of the spring means 40. The shoe is then withdrawn from the machine and the heel 20 to be applied thereto is positioned on the attached plate 11 so that the ears 14 of said plate enter the spaced longitudinal slots 64 in the attaching surface of the heel.

Preferably, the ears 14 are perforated and the body of the heel longitudinally bored as at 89 from the breast surface of the heel so that the bore or opening 89 will register with the apertures of the ears 14. Through the medium of a pneumatic hammer 90a, a locking pin 90 is driven into the bore 89 and through the apertures in the ears 14, thus completing the uniting of the heel in a firmly secured manner to the shoe. The removal of the trimmed U-shaped blank from the outsole enables the concaved or cupped attaching surface of the heel to readily fit over the metallic attaching plate 11 and with the outer edges of the attaching surface of the heel in firm and direct contact with the shoe upper, producing the desired smooth finished appearance. In the event the cutting edges 12 on the heel attaching plates 11 are not of sufficient length to reach the breast slits or cuts 18, a supplemental cutter 91, as shown in Figs. 3 and 4, may be attached to the holder or head 8 in order to complete the cutting of the outsole from the forward edges of the plate 36 to the breast slits. The supplemental cutter may be adjusted longitudinally with respect to the head 8 by means of an adjusting screw 92 arranged at the back of the head 8.

From the foregoing description, it will be evident that the present invention provides an improved machine for securing heel attaching plates to the heel seat region of shoe outsoles and wherein the construction of the machine is such that in its cycle of operation, the shoe outsole is first cut in a regulated and carefully controlled manner to produce breast line slits and in the next succeeding operation, a heel attaching plate is secured to the shoe and the outsole trimmed. In conjunction with these operations, the machine includes a gaging mechanism by which perfect control in the matter of the location of the breast line slits is obtained as well as obtaining the proper positioning of the shoe to receive the heel fastening plate. By the provision of the present invention a considerable saving, over previous manufacturing methods, may be effected in the matter of time and costs in the operations of preparing the shoe for the reception of a heel and in the securing of a heel to the prepared heel seat.

What is claimed is:

1. A combined heel plate attaching and fitting machine comprising a frame, shoe supporting means carried by said frame, an adjustable cutter support movable relative to said frame, a pair of cutters carried by said support, means for actuating said cutters to cause the same to produce inwardly extending slits in the outsole of a heelless shoe positioned on said supporting means, and a movable press head carried by said frame, said head being formed to detachably receive a pronged metallic heel attaching plate having a peripheral cutting edge, the said plate when applied to the heel-receiving region of the shoe outsole by the operation of said press head being so disposed that the cutting edges thereof penetrate said outsole to produce a substantially U-shaped cut therein, the latter being joined with the transverse slits so that the surplus material of the outsole disposed beyond the peripheral edges of the plate is removed from the outsole.

2. In a machine of the class described, in combination, means including positioning and operating devices for securing a metallic heel fastening plate to the heel-receiving region of the outsole of an unfinished shoe, a pair of cutters for producing transverse slits in the outsole of said shoe in substantial registration with the breast-line of a heel subsequently connected with said plate, and template regulated means spaced from said cutters for governing the operating positions thereof.

3. A machine for securing heel fastening plates to the heel seats of shoe outsoles comprising a frame, a table carried by said frame, adjustable shoe positioning means mounted on said table, a cutter support adjustably mounted on said table, a pair of movable spaced cutters carried by said support, means for actuating said cutters to cause the latter to produce transversely extending slits in substantial registration with the heel breast-line of the outsole of a shoe held in engagement with said positioning means, and a press including a movable head formed to detachably receive a pronged metallic heel fastening plate, cutting means provided adjacent the periphery of a heel plate carried by said head, said press serving to force a plate carried by the head thereof into secured engagement with the heel region of the shoe and simultaneously therewith to cut said outsole along the margins of said plate whereby to shape the outsole to receive the cupped attaching face of a shoe heel.

4. A heel plate attaching and fitting machine comprising, in combination, a pair of spaced cutters for producing substantially transversely disposed slits extending inwardly from the edges of a shoe outsole in substantial registration with the breast-line of a heel to be applied to the outsole, and a press formed to detachably support a heel securing plate, said plate being formed with peripheral edges of sufficient depth to penetrate the shoe outsole when said plate is forced by said press into secured engagement with the heel receiving area of a shoe, the cuts produced in the outsole by said plate being merged with said transverse cuts to produce a trimmed heel seat for said plate.

5. A heel plate attaching and fitting machine comprising a frame, adjustable work positioning means for receiving the heel region of an inverted last carried unfinished shoe, with the outsole of said shoe in a substantially horizontal plane, a pair of spaced movable cutters adjustably carried in connection with said frame, means for actuating said cutters to cause the latter to produce inwardly extending transverse slits in the edges of the outsole of a shoe held in engagement with said positioning means, and a press carried by said frame having a movable head formed to detachably receive a pronged metallic heel fastening plate, said plate being provided with peripheral cutting edges, whereby when said press is actuated to force the prongs of said plate into clinching engagement with the heel receiving region of said outsole, the cutting edges of said plate penetrate said outsole and operate in conjunction with said first-named cutters to trim the outsole of surplus material.

6. A heel plate attaching and heel-seat fitting machine comprising a frame, positioning means for retaining the heel receiving region of an unfinished last mounted shoe in a predetermined position with respect to said frame, a pair of knives adjustably mounted in connection with said frame, pneumatically actuated means for effecting the operation of said knives, whereby

to cause the latter to produce inwardly extending transverse slits in the edges of the outsole of a shoe in engagement with said positioning means, said slits being disposed to register substantially with the breast-line of a heel to be attached to the shoe, and a pneumatically operated press including a movable head, said head being formed to detachably carry a pronged metallic heel attaching plate, said plate being provided with marginal cutting edges formed to penetrate said outsole when said press is operated to force said plate into secured engagement with the heel-receiving region of said shoe.

7. A heel plate attaching and heel-seat fitting machine comprising: a frame, positioning means for retaining the heel receiving region of an unfinished last mounted shoe in a predetermined position with respect to said frame, a pair of knives adjustably mounted in connection with said frame, pneumatically actuated means for effecting the operation of said knives, whereby to cause the latter to produce inwardly extending transverse slits in the edges of the outsole of a shoe in engagement with said positioning means, said slits being disposed to register substantially with the breast-line of a heel to be attached to the shoe, a pneumatically operated press including a movable head formed to detachably carry a pronged metallic heel attaching plate, said plate being provided with marginal cutting edges formed to penetrate said outsole when said press is operated to force said plate into secured engagement with the heel-receiving region of said shoe, and supplemental cutters carried by said head and disposed to unite the cuts produced in the outsole by the knives with those produced by the cutting edges of said plate.

8. In a heel plate attaching and fitting machine, a frame, a table carried by said frame, a cutter support mounted on said table, a pair of cutters pivotally carried by said support, a press carried by said frame including a movable plate attaching head, a shoe positioning stop carried by said table, a stationary receiver on said table for a heel engaging templet, means for adjusting said cutter support relative to the breast-line of a templet mounted on said receiver, and means for retaining said shoe positioning stop and said cutter support in their adjusted positions with respect to said templet.

9. The method of preparing shoes for receiving heels comprising positioning an unfinished

heelless shoe mounted on a last upon a positioning means, forcing the prongs of a heel attaching metallic plate into clinched engagement with the insole and outsole of the heel receiving portion of the shoe, and simultaneously with the operation of pressing the plate into such clinched engagement, cutting the outsole along the marginal edges of the plate to remove surplus material from the outsole.

10. The method of preparing shoes for receiving heels, the steps which comprise: transversely slitting the edges of the outsole of a heelless unfinished shoe so that the slits will be disposed in registration with the breast-line of a heel to be subsequently applied to the shoe, forcing the prongs of a heel attaching metallic plate into clinching engagement with the insole and outsole of a heel receiving portion of the shoe, and simultaneously with the operation of pressing the plate into such clinched engagement, cutting the outsole along the marginal edges of the plate and merging such cutting action with said slits to remove surplus material from the outsole.

11. The method of preparing unfinished shoes for receiving heels, the steps which comprise removing a substantially U-shaped blank of surplus material from the heel receiving region of a shoe outsole, and simultaneously with the removal of the blank securing to the shoe over the remaining portion of the heel receiving area of the outsole a metallic heel attaching plate.

12. A machine for operating upon shoes comprising a frame, an anvil block secured to said frame for supporting an inverted heelless shoe, a cutter support provided above said anvil block, means for moving said cutter support downward to hold the shoe in engagement with said anvil, cutters movably mounted on said cutter support, and means for imparting movement to said cutters to form transverse slits in the outsole of the shoe adjacent the heel receiving region.

13. The method of preparing shoes for receiving heels, the steps which comprise clamping an inverted heelless shoe on a support, transversely slitting the outsole of the shoe from the edge toward the center adjacent the heel receiving region, and simultaneously forcing the prongs of a metallic heel attaching plate into clinching engagement with the insole and outsole of the shoe and severing the outsole along the marginal edges of the plate.

HIRAM GORDON.
ALBERT C. ROGGE.
